CARPET ANCHORING DEVICE

Russell Goodemoot, Glendale, Calif., assignor, by
mesne assignments, to Mecasco, Inc., a corpo-
ration of California

Application July 22, 1949, Serial No. 106,141

18 Claims. (Cl. 16—16)

1

The present invention relates to fastening devices for anchoring carpets to floors and the like.

An object of the invention is to provide preformed anchoring strips for securing a carpet to a floor, which are capable of properly locating the carpet with respect to an adjacent wall, and which avoid the exposure of raw carpet edges.

Another object of the invention is to provide preformed anchoring strips for securing a carpet to a floor, in which the marginal edge of the carpet is readily guided into the interior of the strips.

A further object of the invention is to provide a generally channel-shaped anchoring strip provided with a guide for insuring proper and easy insertion of the carpet into the strip, in which the guide properly locates the marginal portion of the carpet adjacent the wall of the room.

Yet another object of the invention is to provide carpet anchoring strips capable of clamping about the marginal portions of carpets to prevent unraveling of their threads, such as the catcher threads of chenille rugs or carpeting.

Another object of the invention is to provide comparatively rigid carpeting anchoring strips capable of being nailed to floors at widely spaced points without danger of flexing of the strips between the points at which they are anchored to the floor. Accordingly, installation of the strips is faster, easier and more economical.

A further object of the invention is to provide carpet anchoring strips that can be removed from the floor without damage, enabling them to be re-used, if desired.

This invention possesses many other advantages, and has other objects which may be made more clearly apparent from a consideration of several forms in which it may be embodied. Such forms are shown in the drawings accompanying and forming part of the present specification. These forms will now be described in detail, illustrating the general principles of the invention; but it is to be understood that such detailed description is not to be taken in a limiting sense, since the scope of the invention is best defined by the appended claims.

Referring to the drawings:

Figure 1 is an isometric view, partly in section, of a carpet anchoring strip secured to a floor, and with a rug in place about and within the strip;

Fig. 2 is a top plan view of a plurality of carpet anchoring strip members joined together;

Fig. 3 is a top plan view of a carpet anchoring member for use at a corner of a room;

2

Fig. 4 is a cross-section through a carpet anchoring strip, rug and room;

Fig. 5 is a cross-section, similar to Fig. 4, disclosing a modified form of carpet anchoring strip, in an initial position;

Fig. 6 is a view similar to Fig. 5, disclosing the carpet anchoring strip in its final position securing the carpet in place;

Fig. 7 is a cross-section disclosing another form 10 of carpet anchoring strip installed in a room;

Fig. 8 is an isometric view, partly in section, disclosing another embodiment of carpet anchoring strip.

In the form of invention shown in Figs. 1 to 4, 15 inclusive, a carpet anchoring strip 10 is preformed to provide a generally channel or U-shaped cross-section. The interior of the channel member is adapted to receive the marginal portion of a carpet or rug C.

20 The channel shaped carpet strip 10 may be made of any convenient length and of any suitable material, such as light gauge sheet metal. The channel member includes a bottom flange 11 having an outer, upwardly directed, inclined spacer and guide portion 12 adapted to be disposed against a wall or wall base W. The top flange 13 of the channel terminates inwardly of the outer edge 14 of the inclined guide, and may be disposed substantially parallel to the bottom flange 11 by the interconnecting web or base 15 of the channel member itself. If desired, the outer margin of the top flange 13 may be folded upon itself to provide a rounded edge 16.

At spaced intervals along its length, the top flange 13 is notched, or cut out, to form openings 17 through which a hammer (not shown) can operate to drive nails 18, inserted through holes 19 in the bottom flange 11, into the floor F of the room. The bottom flange nail holes 19 and the top flange openings 17 thereabove may be placed 35 at suitable intervals along the length of the strip. As disclosed in the drawings, they are provided at the ends of the strip. One end of the strip 10 may constitute a female portion 20 and the end

40 21 of an adjacent strip 22 may be reduced in size for insertion into the female portion 20, thereby 45 assembling the strip members together to provide the desired length along the floor. The openings 17 in the top flanges 13 of the adjoining male and female ends 20, 21 combine to provide 50 a single opening through which a hammer head can be readily manipulated, the nail holes 19 in each strip end overlapping and being in alignment with one another.

55 For the purpose of attaching the carpet C to

the strip and prevent its inadvertent removal, a plurality of anchoring teeth or pins 23 project upwardly from the top flange 13. These pins are inclined in a direction toward the rounded edge 16 of the top flange, and may be formed by punching them upwardly from the top flange, or the teeth 23 may be separately formed and secured, as by welding, to the top flange.

The strip 10, formed of as many sections as are required, is placed upon the floor F, with the spacer guide 12 abutting the wall W of the room. The nails 18 are then inserted through the openings 17 and aligned holes 19 and are driven into place by the head of a hammer. In this manner, the strip is firmly secured to the floor. A rug pad P is then placed upon the floor, with its edge abutting the web portion 15 of the channel strips. Ordinarily, the pad is of the same height as the web.

The rug or carpet is then placed upon the pad P and its marginal portions inserted through the space 24 between the rounded edge 16 of the top flange and the wall W. This portion is guided into the channel by the inclined spacer portion 12 of the bottom flange 11. The marginal carpet edge can be fed into the channel, its reverse movement being prevented by the embedding of the anchoring pins 23 into the carpet material. In view of the fact that these pins 23 are inclined toward the wall, the slack can be taken up in the carpet merely by pressing it toward the wall, the carpet material riding off the pins, and then being gripped by the pins when the carpet tends to shift in a reverse direction.

A corner member 25 is disclosed in Fig. 3. This member is made in exactly the same manner as the carpet strips 10 heretofore described, except that adjacent strip portions have beveled or mitered corners 26 abutting one another, which can be suitably attached to one another. Each beveled portion may be secured to the floor F to hold the mitered corners in abutment, or the corners themselves may be attached to one another, as by welding.

In the form of invention disclosed in Fig. 7, the carpet anchoring strip 10a may be secured to a concrete floor G by being anchored directly thereto upon pouring of the floor. Thus, the bottom flange 11a is provided with a sheet metal angle strip 27 suitably secured thereto, as by use of welding material 28. The top portion 29 of the strip is attached to the lower surface of the bottom flange 11a, while the depending leg 30 of the strip 27 is disposed downwardly and is inclined away from the plane of the wall W.

The strip 10a is properly supported, with its inclined spacer and guide 12a abutting the wall, and the concrete floor G is then poured under the strip and around the flange 30. When the concrete hardens, the flange portion 30 is firmly anchored to the concrete, and thereby prevents the strip 10a from being removed from the concrete floor.

The carpet C may be inserted in the strip 10, and the teeth 23a of the strip anchored to the carpet, in the same manner as was disclosed in the other form of the invention.

It is apparent that the inclined spacer and guide 12 serves to space the outer edge 16 of the top flange a proper distance from the wall, allowing sufficient room 24 for insertion of the carpet into the channel shaped member. In addition, it serves as a guide for feeding the carpet readily into the channel without difficulty.

Each carpet anchoring strip section 10 can be

made of any suitable length. For example, it could be made in two-foot lengths, which may be carried and handled conveniently. The lengths, as described above, are joined together to provide a strip of the desired extent. If longer lengths are used, the holes 19 and the openings 17 in the bottom and top flanges 11, 13 would be provided at intermediate points along the strip. Although the strip is made of sheet metal which can be relatively thin, its preforming into a channel shape makes the entire structure comparatively rigid and requires that the strip be nailed, or otherwise secured, to the floor at comparatively widely spaced intervals. As an example, the spacing of the nails two or three feet apart is sufficient to hold the entire strip structure firmly anchored to the floor F and properly related to the wall W of the room. Such wide spacing enables the installation to be made in a more rapid, easier and economical manner. As shown in Fig. 2, it is only necessary to couple the sections to one another and drive nails 18 through the sections into the floor at each strip joint 20, 21.

In view of the fact that the marginal portion 25 of the carpet C is turned under and into the strip, no raw edges are exposed. The carpet is laid substantially flush against the wall W in a smooth and attractive manner.

In the event that the carpet is to be removed from the floor, it need merely be stretched toward the wall to slide it off the anchoring pins 23. The carpet can then be withdrawn from the anchoring strip 10. The anchoring strip can also be removed merely by pulling the nails 18 from the floor, without damaging the strip itself. This enables the strip to be re-used at the same or another location.

In the form of invention disclosed in Figs. 5 and 6, a carpet anchoring strip 10b is provided for clamping the marginal portion of the carpet or rug C and for preventing unraveling of its threads. This strip is of essentially the same channel shape as the other anchoring strip 10, but is initially formed with the top and bottom flanges 13b, 11b making an obtuse angle relative to one another; so as to provide a relatively wide opening at its outer portion. The top flange 13b has inclined teeth 23b, as in the other form of the device, and it is also bent or folded upon itself at an intermediate portion to form a downwardly extending longitudinal rib 35. In a similar manner, the lower flange has a bend or reverse fold 36 to provide an upwardly projecting longitudinally extending rib which is out of alignment with the upper rib 35. As disclosed in the drawings, the lower rib 36 is disposed forwardly of the upper rib 35 by a certain distance.

The strip 10b is disposed across the floor F and is secured in place by the nails 18a. The carpeting C, which may be chenile, possessing catcher threads T that tend to unravel, is then inserted around the upper edge 16b of the flange 13b and into the channel member. Thereafter, the top flange 13b is bent downwardly toward the bottom flange 11b. This causes the ribs 35, 36 to approach and overlap one another, in order to clamp the marginal portion of the carpet between the ribs, and also between the ribs and the flanges 11b, 13b opposite the respective ribs. The location of the ribs 35, 36 and the extent of their projection into the channel space is determined so that a substantial clamping force can be exerted upon the threads of the carpet. This force is of such an extent as to prevent pulling

or unraveling of the threads, and especially the catcher threads T.

When the top flange 13b is swung downwardly toward the bottom flange 11b, firm clamping of the carpet to the channel 10b is assured, when the top flange is parallel to the bottom flange and the floor. This arrangement insures the disposition of the carpet along a flat, horizontal surface.

In all other respects, the channel strip disclosed in Figs. 5 and 6 is essentially the same as the channel strips disclosed in Figs. 1 to 4, inclusive, and Fig. 7.

An anchoring strip for use across thresholds, or in areas where no wall is present, is disclosed in Fig. 8. This anchoring strip 40 is of generally angled or L shaped section, the top flange 41 of the strip having its outer edge 42 exposed, with the inner portion of the flange merging into a downwardly extending vertical web 42a which engages the floor F and positions the top flange 41 in inclined relation to the floor, so that there is no abrupt line of demarcation between the floor surface itself and the strip. The strip is secured to the floor by nails 18c and is provided with anchoring pins 23c inclined in a direction toward the outer margin 42 of the strip, to grip the rug in the same manner as in the other forms of the invention.

The strip 40 is secured to the floor across the doorway, or other opening, and the rug pad P placed on the floor F with its outer edge engaging the web 42a of the strip. The rug C is then placed over the pad, and its marginal edge E disposed over the strip so that the pins 23c embed themselves into the rug material. Ordinarily, at such exposed points the rug is provided with a suitable binding B.

Because of the inclination of the strip 40 to the floor, the marginal edge E of the rug is also given an inclination, to avoid any abrupt changes between the bare floor surface and the carpeted floor.

The inventor claims:

1. A carpet anchoring device, comprising a pre-formed strip of generally channel-shaped cross-section having a central web and spaced top and bottom flanges extending forwardly from said web toward the wall of a room in which said device is to be placed, said bottom flange extending forwardly a substantially greater distance than said top flange to project beyond said top flange and provide a wall engaging outer edge on said bottom flange, the extent of projection of said bottom flange beyond said top flange being substantially the same as the thickness of a carpet to be placed over and within the strip between its flanges.

2. A carpet anchoring device, comprising a strip of generally channel-shaped cross-section having a central web and spaced top and bottom flanges extending forwardly from said web, said bottom flange extending forwardly a substantially greater distance than said top flange to project beyond said top flange and provide a wall engaging outer edge on said bottom flange, the extent of projection of said bottom flange beyond said top flange being substantially the same as the thickness of a carpet to be placed over and within the strip between its flanges, and carpet anchoring pins extending upwardly from said top flange and inclined forwardly away from said central web.

3. A carpet anchoring device, comprising a strip of generally channel-shaped cross-section

having a central web and spaced top and bottom flanges extending forwardly from said web, the forward portion of said bottom flange being inclined upwardly and outwardly at an obtuse angle to the remainder of said bottom flange and extending forwardly beyond the top flange by a distance substantially the same as the thickness of the carpet to be placed upon the top flange and within the strip between said flanges.

4. A carpet anchoring device, comprising a strip of generally channel-shaped cross-section having a central web and spaced top and bottom flanges extending forwardly from said web, the forward portion of said bottom flange being inclined upwardly and outwardly and extending forwardly beyond the top flange, and carpet anchoring pins extending upwardly from said top flange.

5. A carpet anchoring device, comprising a pre-formed strip of generally channel-shaped cross-section having a central web and spaced top and bottom flanges extending forwardly from said web, said bottom flange extending forwardly a substantially greater distance than said top flange to project beyond said top flange, the extent of projection of said bottom flange beyond said top flange being substantially the same as the thickness of a carpet to be placed over and within the strip between its flanges, and means underlying said top flange and extending from said bottom flange for anchoring said strip to a floor.

6. A carpet anchoring device, comprising a strip of generally channel-shaped cross-section having a central web and spaced top and bottom flanges extending in the same direction forwardly from said web, said bottom flange extending forwardly a substantially greater distance than said top flange to project beyond said top flange and provide a wall engaging forward edge on said bottom flange, the extent of projection of said bottom flange beyond said top flange being substantially the same as the thickness of a carpet to be placed over and within the strip between its flanges, said top flange having one or more openings to enable the placing of fastening elements through said bottom flange for securing said strip to a floor.

7. A carpet anchoring device, comprising a strip of generally channel-shaped cross-section having a central web and spaced top and bottom flanges extending forwardly from said web, the forward portion of said bottom flange being inclined upwardly and outwardly at an obtuse angle to the remainder of said bottom flange and extending forwardly beyond the top flange to provide a wall engaging outer edge on said bottom flange, the extent of projection of said bottom flange beyond said top flange being substantially the same as the thickness of a carpet to be placed over and within the strip between its flanges, said top flange having one or more openings to enable the placing of fastening elements through said bottom flange for securing said strip to a floor.

8. A carpet anchoring device: comprising a plurality of strips of generally channel-shaped cross-section, each strip having a central web and spaced top and bottom flanges extending forwardly from said web, said bottom flange extending forwardly a substantially greater distance than the top flange to project beyond said top flange, the end of one of said strips being shaped to fit snugly within the end of an adjacent strip to form a joint, said top flanges having openings at said joint to enable the placing of

a fastening element through said bottom flanges at said joint for securing said strips to a floor.

9. A carpet anchoring device, comprising a strip of generally channel-shaped cross-section having a central web and spaced top and bottom flanges extending forwardly from said web, said bottom flange extending forwardly a substantially greater distance than said top flange to project beyond said top flange and providing a wall engaging outer edge on said flange, the extent of projection of said bottom flange beyond said top flange being substantially the same as the thickness of a carpet to be placed over and within the strip between its flanges, and means on said flanges extending toward each other for clamping a carpet therebetween.

10. A carpet anchoring device, comprising a strip of generally channel-shaped cross-section having a central web and spaced top and bottom flanges extending forwardly from said web, the forward portion of said bottom flange being inclined upwardly and outwardly at an obtuse angle to the remainder of said bottom flange and extending forwardly beyond the top flange to provide a wall engaging outer edge on said bottom flange, the extent of projection of said bottom flange beyond said top flange being substantially the same as the thickness of a carpet to be placed over and within the strip between its flanges, and means on said flanges extending toward each other for clamping a carpet therebetween.

11. A carpet anchoring device, comprising a strip of generally channel-shaped cross-section having a central web and spaced top and bottom flanges extending forwardly from said web, the forward portion of said bottom flange being inclined upwardly and outwardly at an obtuse angle to the remainder of said bottom flange and extending forwardly beyond the top flange to provide a wall engaging outer edge on said bottom flange, the extent of projection of said bottom flange beyond said top flange being substantially the same as the thickness of a carpet to be placed over and within the strip between its flanges, and longitudinally extending ribs projecting inwardly from each flange toward each other for clamping a carpet therebetween.

12. A carpet anchoring device, comprising a strip of generally channel-shaped cross-section having a central web and spaced top and bottom flanges extending forwardly from said web, the forward portion of said bottom flange being inclined upwardly and outwardly at an obtuse angle to the remainder of said bottom flange and extending forwardly beyond the top flange to provide a wall engaging outer edge on said bottom flange, the extent of projection of said bottom flange beyond said top flange being substantially the same as the thickness of a carpet to be placed over and within the strip between its flanges, and longitudinally extending ribs projecting inwardly from each flange toward each other for clamping a carpet therebetween, said top flange having one or more openings therein to permit fastening elements to be inserted through said bottom flange for securing said strip to a floor.

13. A carpet anchoring device, comprising a strip of generally channel-shaped cross-section having a central web and spaced top and bottom flanges extending forwardly from said web, the forward portion of said bottom flange being inclined upwardly and outwardly and extending forwardly beyond the top flange, longitudinally extending ribs projecting inwardly from each

flange toward each other for clamping a carpet therebetween, said top flange having one or more openings therein to permit fastening elements to be inserted through said bottom flange for securing said strip to a floor, and carpet anchoring pins extending upwardly from said top flange.

14. A carpet anchoring device, comprising a preformed strip of generally channel-shaped cross-section having a central web and spaced top and bottom flanges extending forwardly in the same direction from said web toward the wall of a room in which said device is placed, said bottom flange extending forwardly a substantially greater distance than said top flange to project beyond said top flange and provide a wall engaging outer edge on said bottom flange, the extent of projection of said bottom flange beyond said top flange being substantially the same as the thickness of the carpet to be placed over and within the strip between its flanges, said bottom flange having holes underlying said top flange for enabling said strip to be secured to a floor.

15. A carpet anchoring device, comprising a strip of generally channel-shaped cross-section having a central web and spaced top and bottom flanges extending forwardly in the same direction from said web, said bottom flange extending forwardly a substantially greater distance than said top flange to project beyond said top flange and provide a wall engaging outer edge on said bottom flange, the extent of projection of said bottom flange beyond said top flange being substantially the same as the thickness of a carpet to be placed over and within the strip between its flanges, carpet anchoring pins extending upwardly from said top flange and inclined forwardly away from said central web, said bottom flange having one or more holes underlying said top flange for enabling said strip to be secured to a floor.

16. A carpet anchoring device, comprising a preformed strip of generally channel-shaped cross-section having a central web and spaced, parallel top and bottom flanges extending forwardly in the same direction from said web, said bottom flange extending forwardly a substantially greater distance than said top flange to project beyond said top flange and provide a wall engaging outer edge on said bottom flange, the extent of projection of said bottom flange beyond said top flange being substantially the same as the thickness of a carpet to be placed over and within the strip between its flanges, carpet anchoring pins extending upwardly from said top flange and inclined forwardly away from said central web, said bottom flange having one or more holes therein underlying said top flange for enabling said bottom flange to be secured to a floor.

17. A carpet anchoring device, comprising a strip of generally channel-shaped cross-section having a central web and spaced top and bottom flanges extending in the same direction forwardly from said web, said bottom flange extending forwardly a substantially greater distance than said top flange to project beyond said top flange and provide a wall engaging forward edge on said bottom flange, the extent of projection of said bottom flange beyond said top flange being substantially the same as the thickness of a carpet to be placed over and within the strip between its flanges, said top flange having one or more openings to enable the placing of fastening elements through said bottom flange for securing said strip to a floor, and carpet anchor-

ing pins extending upwardly from said top flange and inclined forwardly away from said central web.

18. A carpet anchoring device, comprising a strip of generally channel-shaped cross-section having a central web and spaced top and bottom flanges extending forwardly in the same direction from said web, said bottom flange extending forwardly a substantially greater distance than said top flange to project beyond said top flange and provide a wall engaging outer edge on said bottom flange, the extent of projection of said bottom flange beyond said top flange being substantially the same as the thickness of a carpet to be placed over and within the strip between its flanges, means on said flanges extending toward each other for clamping a carpet therebetween, and carpet anchoring pins extend-

ing upwardly from said top flange and inclined forwardly away from said central web.
